(57) **CLAIM**

The ornamental design for a “cleaning implement,” as shown and described.

DESCRIPTION

FIG. 1 is a perspective view of a “cleaning implement” incorporating the design;

FIG. 2 is a top view thereof;

FIG. 3 is a front view thereof;

FIG. 4 is a bottom view thereof;

FIG. 5 is a rear view thereof;

FIG. 6 is a side view thereof; and,

FIG. 7 is another side view thereof.

The broken lines showing bristles are for illustrative purposes only and form no part of the claimed design.
